United States Patent Office.

CHARLES W. BLAKESLEE, OF WATERTOWN, CONNECTICUT, ASSIGNOR TO
HIMSELF AND JOSEPH PECK, OF SAME PLACE.

Letters Patent No. 105,415, dated July 19, 1870.

IMPROVED TRACE-FASTENING.

The Schedule referred to in these Letters Patent and making part of the same

To all whom it may concern:

Be it known that I, CHARLES W. BLAKESLEE, of Watertown, in the county of Litchfield and State of Connecticut, have invented a new and useful Improvement in Trace-Locks; and I do hereby declare that the following is a full and exact description of the same, reference being had to the accompanying drawing and to the letters of reference marked thereon.

This invention consists of an improved construction of trace-lock, the details of which are hereinafter fully set forth.

In the drawing—

Figure 1 represents a plan view;

Figure 2, a central sectional elevation;

Figure 3, a plan view with the cover removed; and

Figure 4, a plan view of the cover detached.

This lock is composed mainly of three pieces, the piece A forming the larger part of the device. It is made by swaging or casting, as are the other corresponding parts.

At the smaller end it is constructed with a slot, *a*, of proper size to pass over the head of the bolt in the end of the whiffletree or other part.

The other end is larger, and recessed, to adapt it to receive the end of the trace or other strap to which it is to be attached. This recess extends, somewhat narrowed, to near the extremity of the open slot, its sides being shown at *b b*, in fig. 3 of the drawing. In this recess slides the piece B, formed as shown in figs. 1 and 3. Its forward end is slightly notched, to correspond to the round shank of bolt or button, over which the lock passes.

The rear end is formed with a projecting flange, covering the spindle and spring, and is perforated lengthwise, to receive the end of the said spring.

The rod or spindle which holds the spring in place is properly secured to the bottom of the open slot, or may form part of the metal of it.

When in place, one end of the spring rests on the rod *c*, and against the shoulder *d*, the other end being in the hole *g*, (figs. 2 and 3.)

The length of this spiral spring is such as to push the slide quite to the end of the slot.

From the upper side of the slide is a projection, *h*, passing through the detachable side *i*, and allowing the slide to be manipulated in locking the device upon its proper button.

Over the whole is placed the detachable side or cover *i*, which fits down snugly over all the parts, making the exterior smooth and uniform.

Having thus fully described my invention,

What I claim as new, and desire to secure by Letters Patent of the United States, is—

The described lock, formed of the described parts, the main part A, with its slot *a*, recesses, shoulder *d* with its spindle *c*, the slide with its socket *g* and projection *h*, and the cover *i*, all constructed and arranged to operate as set forth.

This specification signed and witnessed this 28th day of may, 1870.

CHARLES W. BLAKESLEE.
